HAMMER STAMP

Application filed April 15, 1929. Serial No. 355,124.

Our invention refers to an improvement in hammer stamps for the purpose of stamping sheet metal or any other similar commodity having a substantially flat surface, against which a stamp may be thrust for imprinting thereon, in the manner of a hammer, having an operating handle. In such stamps, it is desirable that there be interposed between the handle and the stamping face means providing a sufficient degree of resiliency adapting the face of the stamp to effect good contact, independent of variations in exact parallelism between the surface to be stamped and the stamping surface, when used.

15 The device consists generally of a stamp, in either single or double form, having an operating handle so connected as to permit of a limited degree of flexibility whereby to compensate for any lack of accuracy in delivering 20 the blow so as to allow the stamping face to automatically adjust itself, under the impulse of the blow.

In its construction, our stamp is composed of single or double head portions composed 25 of rubber or other suitable resilient or flexible material, a handle and means connecting it with the stamping member or members, together with detachable stamping heads secured thereto. Such heads are also of rubber having on their faces any desired imprinting characters and are provided with an inner reinforcing plate and securing studs, with certain other features of construction and advantage, as shall be more fully herein- 30 after described.

The device is in its principal elements similar to that shown in a companion application filed herewith Ser. No. 355,123.

40 Referring to the drawings showing preferred constructions:

Fig. 1 is a view in side elevation, showing the double head form of stamp complete;

45 Fig. 2 is a plan view of the upper stamping face thereof;

Fig. 3 is a similar view of the opposite or lower stamping face;

Fig. 4 is an enlarged cross sectional view on the line IV—IV of Fig. 1;

Fig. 5 is a perspective view showing the 50 under side of the removable stamping unit.

In the drawings, the main inner portion of the stamp is in the form of a main hammer head 2 of rubber or the like having an enlarged outer body of circular or other form 55 adapting it to receive and be secured to the detachable stamping head 2b.

The body portion of the head 2 may be of any suitable form, and is provided with an inner diminishing or narrowed neck 6 having a flat opposing face for attachment to and connection with the end 7 of an operating handle 8. A central connecting bolt 9 is imbedded and vulcanized by its head and shank portion within the middle of one of the heads 65 2 and projects sufficiently far beyond its smaller attaching face to extend through a registering hole in the end of the handle and therebeyond, for attachment to the companion head 2a at the opposite side, as in Fig. 4. 70

In such construction the opposite head 2a is generally similar to head 2 above described, but is provided with a centrally imbedded and vulcanized sleeve nut 11 of any suitable form. 75

The nut 11 makes screw engagement with the threaded outer end of bolt 9 by turning and tightening thereon, by which the two heads are tightly clamped together and against the opposite side faces of the handle terminal 7. By such construction head 2a may be readily connected to or disconnected from the other head 2, for substitution as to one or both, of other similar heads of different size or for any other purpose. 80

By such construction the comparatively soft rubber body of the heads surrounding the bolt and nut respectively provides ample flexibility to adapt the face of either supplemental stamping head 2b to make a good 85 90

stamping impression, whether brought fairly and evenly against the surface to be stamped, or at a considerable angle thereto by the operator.

5 When there is any such variation and the face of either head is brought against a surface with which it would not ordinarily register, due to any angular relation, the flexibility of the head connection with the handle permits of automatic adjustment and 10 good stamping results, under impact of the blow.

The supplemental stamping head 2b at either side is provided with any suitable 15 printing letters, figures or characters, as indicated on the face views, Figs. 2 and 3. Such characters are ordinarily molded in the rubber, as at 3, or may be in the form of detachable inserted type 4, all mounted on 20 a common plane.

For the purpose of reinforcing the head 2b closely adjacent to the area embodying such characters, and for providing a substantial attaching base, the head 2b is provided with 25 a thin reinforcing disk or plate 5. Such plate is tightly secured to the inner face of head 2b by any suitable means as cementing, vulcanizing, etc., and may be of suitable material, as brass.

30 Heads 2 and 2a are each provided with transverse reinforced bolt holes having inserted tubular lining sleeves 13 extending through from one side to the other, and vulcanized to the rubber, as in Fig. 4.

35 Head 2b is provided with a corresponding series of similarly located and spaced connecting bolts 14 having enlarged reinforcing beveled heads 15, the flat inner ends of which are soldered or welded to the face of plate 5. The outer ends of sleeves 13 are inwardly 40 beveled to receive heads 15, so that when the stamping head 2b is in position, the parts fit snugly and tightly together, and are held by the securing nuts 16.

45 One advantage of the comparatively thin plate 5 when tightly secured to the stamping head 2b is that it may be readily bent to a concave form for attachment to the convex face of the main head or base, as in making a rocker stamp, capable of rolling motion over the surface being stamped.

By such construction it will be seen that a supplemental head may be substituted for another at either side, having any suitable or 55 different form, kind, or arrangement of stamping characters, either molded in the rubber face of the head itself, or separately attached as by the stamping characters 4a.

The latter may be of the split wedge type 60 like that shown in prior patent of W. J. Pannier, Jr., No. 1,191,820. In such case their divided bases bear against the inner socketed surface of the head, closely adjacent to plate 5, providing a sufficiently firm and 65 comparatively rigid opposing bearing.

The construction and operation of the invention will be readily understood and appreciated by all those familiar with hand operated stamping devices. It is comparatively simple in construction capable of easy and rapid change or substitution, and may be used at considerable speed by alternately striking upon an inking pad and then upon a surface to be marked, without the necessity for any special skill. 70

It will be understood that one of the heads, as 2, alone may be used without the other by connecting its bolt 9 with the handle 8 by securing nuts, as in Fig. 6 of our companion application Ser. No. 355,123, filed herewith. 80

Also that the material of the supplemental head 2b may be of rubber, metal, or any other suitable material.

The device is extremely useful, very durable, and may be made in different shapes, designs, sizes, weights, or otherwise changed or varied by the skilled mechanic, but all such changes are to be understood as within the scope of the following claims. 85

What we claim is:

1. The combination with a resilient head having a flat outer face and a series of bolt openings having sleeve linings therein, of a separable stamping head provided with a base plate secured to the inner face of the head 95 and bolts secured to the plate and extending through the bolt hole linings.

2. The combination with a resilient head having a flat outer face and a series of bolt openings having sleeve linings therein inwardly beveled at their outer ends, of a separable stamping head provided with a base plate secured to the inner face of the head and bolts having beveled heads secured to the plate having interfitting engagement with the sleeve linings. 105

3. A separable stamping head of rubber or the like provided with outer stamping characters and an inner flat base plate vulcanized to the head, and a series of securing bolts having enlarged heads welded to the plate and extending at right angles thereto. 110

4. The combination with a resilient supporting head having an inner handle attaching neck and an outer enlarged flat face portion, of a separable stamping head provided with an inner fixedly attached base plate having connecting bolts extending through the flat face portion securing the stamping head thereto. 115

5. The combination with a holding handle having a perforated flat face terminal, of a hammer stamp comprising a resilient head having an inner integral flat end neck engaging the handle terminal and a laterally enlarged flange-like base having bolt openings therethrough, and a stamping head provided with holding bolts extending through and secured in the bolt openings. 125

6. The combination with a holding handle 130

having a perforated flat face terminal, of a hammer stamp comprising a resilient head having an inner integral flat end neck engaging the handle terminal and a laterally enlarged flange-like base having bolt openings therethrough, and a stamping head provided with an inner reinforcing plate connected with the stamping head and having holding bolts extending through and secured in the bolt openings.

10 In testimony whereof we hereunto affix our signatures.

WILLIAM J. PANNIER, JR.
OSCAR M. PANNIER.
